(57) **CLAIM**

I claim the ornamental design for a rifle rest, as shown and described.

DESCRIPTION

FIG. 1 is a top, front, and right side perspective view of a rifle rest according to my design;

FIG. 2 is a top plan view thereof;

FIG. 3 is a bottom plan view thereof;

FIG. 4 is a right elevational view thereof;

FIG. 5 is a left elevational view thereof;

FIG. 6 is a front elevational view thereof; and,

FIG. 7 is a rear elevational view thereof.
